Primary Examiner — Garth Rademaker*Assistant Examiner* — Omeed Agilee*(74) Attorney, Agent, or Firm* — George H. Leal**CLAIM**

The ornamental design for an absorbent article package, as shown and described.

DESCRIPTION

FIG. 1 is a perspective front, top perspective view of an absorbent article package showing the new design; FIG. 2 is a front view of the design shown in FIG. 1; FIG. 3 is a right side view of the design shown in FIG. 1; FIG. 4 is a back view of the design shown in FIG. 1; FIG. 5 is a left side view of the design shown in FIG. 1; FIG. 6 is a top view of the design shown in FIG. 1; and, FIG. 7 is a bottom view of the design shown in FIG. 1. Only the solid lines shown in the figures described above form the claimed design. Broken lines shown in the drawings depict environmental subject matter and form no part of the claimed design.
